ATTORNEY

UNITED STATES PATENT OFFICE.

EDWIN J. MINNICH, OF SALEM, OREGON.

NAIL-EXTRACTOR.

1,227,063.

Specification of Letters Patent. Patented May 22, 1917.

Application filed August 11, 1916. Serial No. 114,425.

To all whom it may concern:

Be it known that I, EDWIN J. MINNICH, a citizen of the United States, residing at Salem, in the county of Marion and State of Oregon, have invented certain new and useful Improvements in Nail-Extractors, of which the following is a specification.

This invention relates to an improved nail and tack hammer and the primary object of the invention is to provide an attachment for coöperating with the claws of the hammer whereby a rusty or slippery nail may be withdrawn from the place in which it is embedded without employing the common expedient of a block for raising the hammer as is done with the hammers now generally in use.

A further object of the invention is the provision of a pivot pawl adapted to grip the shank of the nail and to coöperate with one of the claws of the hammer for withdrawing the nail thereby facilitating the extraction of a headless nail or a nail of unusual length.

As a further object of the invention the device is provided with a pivot pawl, the pivotal movement of which is limited so that the gripping edge of the pawl is restricted in its movement for obviating the possibility of severing the shank of the nail.

A further object of this invention is the provision of a nail and tack hammer which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, where in is illustrated the preferred form of my invention, in which;

Figure 1 is a side elevation of a hammer head shown in gripping engagement with a nail.

Fig. 2 is a similar view, parts of the hammer head being shown in section.

Fig. 3 is a section on the line 3—3 of Fig. 1.

Fig. 4 is a detail perspective view of the gripping pawl.

Fig. 5 is a fragmentary section on the line 5—5 of Fig. 1.

Fig. 6 is a fragmentary section on the line 6—6 of Fig. 1.

The hammer is provided with the usual handle 1 having one end secured in the socket 2 which forms a part of the hammer head. The striking end 3 of the hammer extends from one side of the hammer head and the claws 4 and 5 project over the opposite side and are curved as clearly shown by Figs. 1 and 2 of the drawing.

By referring to Fig. 3 it will be noted that the claw 5 is of a greater thickness than the claw 4. The claw 5 is provided with a horizontally extending groove 6 which is substantially circular in transverse section and the groove communicates with the space 7 between the claws 4 and 5. Mounted within the groove is the cylindrical bolt 8 the end 9 of which is beveled and curved to conform to the curvature of the claw 5. The opposite end of the bolt is reduced in diameter to provide the trunnion 10 which is received in the recess 11 formed in the hammer head and in horizontal alignment with the groove 6. Adjacent the end of the trunnion is an annular groove 12 which receives one end of a retaining pin 13 which extends through the side of the hammer head and prevents the displacement of the bolt 8 and permits the same to freely rotate when desired.

As shown by Figs. 4 and 5 of the drawing the trunnion 10 is provided with a segmental cut-out portion or recess 14 which receives one end of a limiting pin 15 which limits the rotary movement of the bolt when the side walls of the recess contact with the pin 15. Integrally formed with the bolt 8 is the gripping pawl 16 which is provided with the sharpened edge 17 for contacting and biting into the shank of the nail when the device is in operation.

When using the device it is merely necessary to place the hammer head in position as shown by Fig. 1 of the drawing so that the nail projects through the space 7 between the claws 4 and 5. Then, by throwing the pawl 16 over into engagement with the shank of the nail, the nail may be withdrawn by pulling upon the hammer handle in the usual manner. The sharpened edge of the gripping pawl 16 will bite into the shank of the nail sufficiently to allow the extraction thereof but the limited rotary movement of the pawl, caused by the limiting pin 15, will prevent the pawl from cutting through the shank of the nail. If the nail is not fully extracted after the limited lever-

age of the hammer handle has been exhausted, the hammer may be moved back to the original position for causing the pawl to grip the shank of the nail at a point farther down so that the remainder of the nail 5 may be extracted.

From the foregoing it will be observed that a very simple and durable nail and tack hammer has been provided, the details of 10 which embody the preferred form. I desire it to be understood however, that slight changes in the minor details of construction may be made without departing from the spirit of the invention or the scope of the 15 claims hereunto appended.

I claim:

1. A nail extractor comprising a hammer having a pair of curved claws, one of the claws provided with a groove disposed at 20 right angles to the longitudinal center line of the hammer socket whereby the groove will be disposed in a horizontal plane when the hammer is set in operative position for extracting a nail, and gripping means rotatably mounted within the groove and adapted 25 to grip a nail independently of the corresponding claw, the said means including a gripping pawl adapted to extend over the space between the said claws and provided 30 with a longitudinally sharpened edge.

2. A nail extractor including a hammer head provided with a socket and a pair of claws, one of the claws having a groove disposed at right angles to the longitudinal center line of the hammer-socket and communicating with the space between the said claws, a cylinder rotatably mounted in the groove, and gripping means carried by the cylinder and adapted to grip a nail independently 40 of the adjacent corresponding claw.

3. A nail extractor including a hammer head provided with a pair of claws, one of said claws being of a greater thickness than 45 the other claw, the said thicker claw being provided with a groove extending toward the main portion of the hammer head and communicating with the space between the said claws, a cylindrical bolt mounted in 50 the groove for rotary movement, gripping means carried by the bolt, and means for limiting the rotary movement of said bolt.

4. A nail extractor including a hammer head provided with a pair of claws, one of 55 said claws being of a greater thickness than the other claw, the said thicker claw being provided with a groove extending toward the main portion of the hammer head and communicating with the space between 60 the said claws, a cylindrical bolt mounted in the groove for rotary movement, gripping means carried by the bolt, one end of the said bolt being reduced in diameter to provide a trunnion, the said hammer head 65 having a recess in alinement with the said

groove for receiving the said trunnion, and means for preventing the displacement of the trunnion from said recess.

5. A nail extractor including a hammer head provided with a pair of claws, one of said claws being of a greater thickness than the other claw, the said thicker claws being provided with a groove extending toward the main portion of the hammer head and communicating with the space between the said claws, a cylindrical bolt mounted in the groove for rotary movement, gripping means carried by the bolt, one end of the said bolt being reduced in diameter to provide a trunnion, the said hammer head having a recess in alinement with the said groove for receiving the said trunnion, the said hammer head having an aperture extending at right angles to and communicating with the said recess, a retaining pin extending through the aperture and coöperating with the said trunnion, the said trunnion having an annular groove for preventing the displacement of the trunnion from said recess.

6. A nail extractor including a hammer head provided with a pair of claws, one of said claws being of a greater thickness than the other claw, the said thicker claw being provided with a groove extending toward the main portion of the hammer head and communicating with the space between the said claws, a cylindrical bolt mounted in the groove for rotary movement, gripping means carried by the bolt, one end of the said bolt being reduced in diameter to provide a trunnion, the said hammer head having a recess in alinement with the said groove for receiving the said trunnion, the said hammer head having an aperture extending at right angles to and communicating with the said recess, a retaining pin extending through the aperture and coöperating with the said trunnion, the said trunnion having an annular groove for preventing the displacement of the trunnion from said recess, means for limiting the pivotal movement of the said bolt including a limiting pin carried by the hammer head and engaging said trunnion.

7. A nail extractor including a hammer head provided with a pair of claws, a cylindrical bolt carried by one of the said claws and adapted for rotary movement, gripping means carried by the bolt, a trunnion carried by the bolt, the said trunnion being provided with an annular groove, and a retaining pin carried by the hammer head and adapted to coöperate with the said groove for preventing the displacement of the said bolt.

8. A nail extractor including a hammer head provided with a recess and a pair of claws, one of the said claws having a groove, gripping means mounted within the said

groove and including a trunnion projected into the said recess, and means carried by the hammer head and adapted to coöperate with the said trunnion for limiting the 5 pivotal movement of the gripping means and preventing the displacement thereof from the said groove.

In testimony whereof I affix my signature in presence of two witnesses.

EDWIN J. MINNICH.
